Patented Sept. 12, 1916.

UNITED STATES PATENT OFFICE.

SELDEN S. GORDON, OF HALESITE, NEW YORK.

HAMMER.

1,197,929.

Specification of Letters Patent. Patented Sept. 12, 1916.

Application filed March 11, 1913, Serial No. 753,560. Renewed July 19, 1916. Serial No. 110,259.

To all whom it may concern:

Be it known that I, SELDEN S. GORDON, a citizen of the United States, residing at Halesite, Long Island, in the county of 5 Suffolk, State of New York, have invented certain new and useful Improvements in Hammers; and I do hereby declare the following to be a full, clear, and exact description of the invention, such as will 10 enable others skilled in the art to which it appertains to make and use the same.

This invention relates to hammers.

The object of the invention resides in the provision of a hammer in which the outer 15 faces of the poll and claw are disposed throughout in a continuous curve whereby a continuously shifting fulcrum is obtained in the extraction of a nail, said extraction being instituted with a long leverage resulting in slow extraction and said leverage 20 constantly decreasing during extraction whereby the rapidity of the extraction is constantly increased.

With the above and other objects in view 25 the invention consists in the details of construction and in the arrangement and combination of parts to be hereinafter more fully described and particularly pointed out in the appended claims.

30 In describing the invention in detail reference will be had to the accompanying drawings wherein like characters of reference denote corresponding parts in the several views, and in which—

35 Figure 1 is a side elevation of a hammer constructed in accordance with the invention, same being shown in the relation it would occupy to a nail when the extraction of the latter is instituted. Fig. 2 a view 40 similar to Fig. 1 showing the hammer in the relation it would occupy to a nail when the extraction of the latter has been substantially completed. Fig. 3 a section on the line 3—3 of Fig. 2, and Fig. 4 a section on 45 the line 4—4 of Fig. 3.

Referring to the drawings the hammer is shown as comprising a head A and a handle B. This head A includes a poll 10 and a claw 11 and is provided centrally with a 50 handle receiving passage 12. The side walls of the passage 12 converge toward each other from each end inwardly so as to produce substantially opposed wedges 13 and

14 which serve to hold the head against disengagement from the handle B, it being obvious that when the handle is driven into the passage 12 it will be forced by the points of the wedges 13 and 14 and that portion of the handle which passes the points of said wedges will expand and lock the head and 60 handle together.

In order that the full extraction of a nail may be accomplished without employing the free end of the poll 10 as a fulcrum the claw 11 is made relatively long and the outer 65 face of both the claws 11 and the poll 10 are disposed in the same curves throughout the entire length of the claw and poll. By this construction it will be apparent that the outer face of the poll and obviate the 70 shifting fulcrum can travel gradually down extreme jump in the positions of the fulcrums which occurs during the final extracting operation when the outer face of the poll is not a continuation of the curve of 75 the outer face of the claw and serves to enable the complete extraction of the nail without excessive bending thereof. It will be noted that the curve of the outer face of the claw 11 constantly approaches the handle 80 B. This construction brings the free end of the claw into substantial parallelism with the handle B so that when the hammer is operated to extract a nail the said handle will be at first disposed substantially parallel to the work so that an upward pull on the handle will effect the extraction. This results in the advantage of effecting extraction with a relative short upward pull rather than a relatively long sidewise and partly 85 downward pull. Another advantage of this construction is that greater lifting power will be gained or the same amount of power 90 will do the work better.

What I claim is:—

1. A hammer comprising a head, a poll, and a claw, the outer face of the head, poll and claw being disposed in a continuous curve from the end of the claw to the end of the poll and the longitudinal axis of the 100 head disposed at right angles to a tangent to a portion of the curve included between the ends of the face.

2. A hammer comprising a head, a poll, and a claw, the outer face of the head, poll 105 and claw being disposed in a continuous

curve from the end of the claw to the end of the poll and the longitudinal axis of the head disposed at right angles to a tangent to a portion of the curve included between the 5 ends of the face, the inner face of the claw being out of parallelism with the inner face of the poll and above the latter.

In testimony whereof, I affix my signature, in the presence of two witnesses.

SELDEN S. GORDON.

Witnesses:

H. L. ROOD,
C. P. HARRIS.

Copies of this patent may be obtained for five cents each, by addressing the "Commissioner of Patents, Washington, D. C."

It is hereby certified that in Letters Patent No. 1,197,929, granted September 12, 1916, upon the application of Selden S. Gordon, of Halesite, New York, for an improvement in "Hammers," an error appears in the printed specification requiring correction as follows: Page 1, transpose lines 70 and 71; and that the said Letters Patent should be read with this correction therein that the same may conform to the record of the case in the Patent Office.

Signed and sealed this 24th day of October, A. D., 1916.

[SEAL.]

F. W. H. CLAY,

Acting Commissioner of Patents.
